UNITED STATES PATENT OFFICE.

FRITZ LOWENSTEIN, OF ROCKAWAY PARK, NEW YORK; JOHN C. WAIT, ADMINISTRATOR OF SAID FRITZ LOWENSTEIN, DECEASED, ASSIGNOR, BY MESNE ASSIGNMENTS, TO RADIO CORPORATION OF AMERICA, A CORPORATION OF DELAWARE.

TRANSMITTER APPARATUS.

Application filed February 25, 1915. Serial No. 10,592.

This invention relates to transmitter apparatus for use in wireless systems of all kinds and especially in radio signaling installations. The principal objects of the invention are to provide transmitter apparatus characterized by relatively simple and compact construction, and by ease of operation; to provide for easy change of wave length or oscillation period to suit different operating conditions; to provide for varying the wave length in both transmitter circuits simultaneously and in syntony; to enable such change of wave length to be made in such manner that correct coupling may be automatically attained for the various wave lengths; to enable change of wave length and also variation of the coupling to be effected from one point of control on the transmitter; and to enable the coupling to be altered without thereby changing the self-inductance of the secondary or antenna circuit. These and other objects of the invention are more fully set forth in the following description and claims.

In most wireless telegraph systems now in practical use, the apparatus at the sending station comprises an antenna included in what is known as the open or radiating circuit, to which circuit energy is supplied by a closed or oscillating circuit, said oscillating circuit in turn being supplied with energy from any suitable source. The oscillating circuit comprises a spark gap, a condenser, a variometer, and an inductance, which inductance usually constitutes the primary of the so-called oscillation transformer. Inductively coupled to the primary of the oscillation transformer and forming a part of the open or radiating circuit is an inductance known as the secondary of the oscillation transformer. According to the best practice, the inductance of the open circuit, instead of being concentrated in the transformer secondary, is distributed between said secondary on the one hand and so-called loading coils on the other, said loading coils being in circuit with the transformer secondary but being so located that there is substantially no mutual induction between the primary and said loading coils. The present invention is directed principally to those parts of the transmitter system comprising the primary and secondary of the oscillation transformer and the loading coils.

The apparatus hereinafter described makes possible the attainment of the above-enumerated objects in a simple and ready manner; and in particular, it enables the wave length in the closed and open circuits to be simultaneously changed with great rapidity and accuracy without disturbing the tune of the set.

In order to make clear the principles of the invention, I have illustrated in the accompanying drawings certain assemblages of apparatus which embody said principles and which have proved successful in practice. It is not intended, however, to limit the invention to the particular forms of apparatus herein disclosed, since said apparatus is capable of various modifications and changes within the scope of the invention. In these drawings—

Fig. 1 is a view in side elevation of transmitter apparatus embodying the principles of the present invention;

Fig. 2 is a plan, and Fig. 3 is a front elevation, of the same;

Figs. 4 and 5 are details, partly in section;

Fig. 6 is a sectional view of the oscillation transformer and auxiliary parts, on a larger scale;

Figs. 7, 8 and 9 are details;

Fig. 10 is a fragmentary detail of another form of coil mounting;

Fig. 11 illustrates diagrammatically the circuit connections involved in the apparatus of the foregoing figures;

Fig. 12 illustrates another form of apparatus within the invention; and

Fig. 13 illustrates diagrammatically the circuit connections corresponding to Fig. 12.

Considering first that form of the apparatus illustrated in Figs. 1 to 11, inclusive, the oscillation transformer consists of spirally wound flat or "pancake" coils 20 and 21 constituting the primary and secondary, respectively, of the transformer. The primary coil is mounted on an elongated insulator hub 22, which, in turn, is mounted on insulator plate 23. The secondary 21 of the oscillation transformer is similarly mounted on an insulator hub 24 secured to insulator plate 25. The insulator hubs 22 and 24 may conveniently be made of wood. For convenience, the insulator plates 23 and 25 will be hereinafter referred to as the front plate

and the rear plate, respectively, of the transmitter. The loading coils 26 may also be of the pancake type as here shown, and may be mounted on a common insulator shaft 27. 5 As many of these loading coils may be provided as is necessary; in this instance, five such coils are shown connected in series. The loading coils are shown as mounted with their axes substantially at right angles to 10 the axis of the secondary coil of the oscillation transformer, mutual self-inductance between said loading coils and secondary coil being thereby practically eliminated. (See Fig. 2.)

15 It will be noted that the primary coil 20 is here shown (Fig. 6) as having its adjacent outer turns spaced farther apart than the inner turns. This is to guard against breakdown due to excessively high differences 20 in potential which may exist between the outer turns of the primary in actual operation. This greater potential difference in the outer turns is due first, to the greater self-inductance per turn on account of the 25 greater diameter of the outer turns; and second, to the fact that when only one or two turns are in use (short wave length operation) the potential difference per turn is greater. Thus in the typical instance 30 shown in the drawings, the space 20^a between the two outermost turns may be about an inch, and the next succeeding space 20^b about three-quarters of an inch; while the remaining spaces 20^c may be each about half an inch.

35 For the purpose of varying the coupling, the primary and secondary of the oscillation transformer are so mounted as to be relatively movable. To this end, either or 40 both of the coils may be movably mounted. In the present example, the coils are axially aligned and the primary is stationary, the front plate of the transmitter carrying said primary being rigidly supported at 28 on 45 the transmitter base 29 (Fig. 1). On the other hand, the rear transmitter plate carrying the secondary is supported on rollers 30 resting on tracks 31, whereby the secondary may be moved toward or away from the primary in the direction of the common axis. Since it is desirable that the secondary and the loading coils shall always remain 50 in the same position with respect to each other in order to avoid changes in the inductance of the secondary circuit when the coupling is altered, means are provided to ensure the attainment of this result. As here shown, the shaft 27 carrying the loading coils is mounted on a carriage 32 which is supported on rollers 33 moving on track 34; and said carriage and the rear plate of the transmitter are mechanically connected for movement in unison as by rigid members 35. By means of this arrangement 55 the transformer secondary and

the loading coils may be moved together as a unit.

The primary of the oscillation transformer may be tapped at any convenient number of points as by movable clips 36 (Fig. 6), 70 and connected by leads 37 to studs or terminals 38 mounted on the front plate of the transmitter. By shifting the movable clips 36 along the spiral conductor the positions of the tapping points are evidently adjustable. In the present example, the primary is tapped off at nine points which are connected, respectively, to nine studs on the front plate. For the sake of convenience in making the connections, two sets of nine studs 80 each are provided on the primary transmitter plate here illustrated, the two sets being arranged on the circumference of a circle. These two sets provide nine independent pairs of studs, each pair having one of its members in one set and the other member in the other set. For the sake of clearness the studs in each set have been numbered from 1 to 9; and it will be seen that the pairs consist of studs located radially opposite each other. In bringing the leads from the tapping-off points on the primary, connection may be made to either stud of a pair, that stud being chosen which makes the wiring 90 the simplest. An electrically conductive bar 39 spans the front transmitter plate and is rotatably mounted thereon in such manner as to sweep duplicate brushes 40 over the two sets of studs and thus to connect the pairs of studs successively, thus making the 100 two members of each pair in effect the same point electrically. While this duplicate arrangement of studs is very convenient, it is not essential, and any other suitable arrangement may be employed. The said bar 39 may be suitably connected as by conductor 41 and lead 41^a to the closed circuit of the 105 oscillation system; while either end of the primary coil 20 (in this instance the outer end) is connected as by lead 42 (Fig. 1) to 110 said closed circuit.

The secondary of the oscillation transformer is tapped in a similar manner and at the same number of points as the primary. Movable clips 43 and leads 43^a connect the tapping-off points to a set of independent studs 44 on the rear plate of the transmitter, this set being here shown as located on the lower portion of said plate and comprising nine studs. Another set of nine 115 studs 45 on the upper portion of the rear transmitter plate is also provided; and these upper studs or terminals are electrically connected, respectively, by suitable means, here shown as comprising metal strips 46, leads 120 46^a and movable clips 47, to adjustable tapping points on the loading coils. For the sake of convenience, said loading coils are wound alternately clock-wise and counter-clockwise, beginning at the centers of the 125 130

coils; so that the connection 48 between the first and second coils is near outer peripheries, whereas connection 49 between the second and third coils is made near the centers of said coils, and so on for the other connections 50, 51. This method of winding the loading coils obviously simplifies their connection in series; but though convenient, it is not essential, and any other suitable method of winding may be employed.

In order to connect any one of the studs 44 of the lower set in series with the corresponding studs 45 of the upper set, an electrically conductive bar is rotatably mounted on the rear transmitter plate. On account of the higher potential difference existing in operation between adjacent studs 45 as compared to that between adjacent studs 44, 20 studs 45 are advantageously spaced farther apart than studs 44. As here shown, both sets are arranged on circular arcs, that on which studs 45 are located having the greater radius. This arrangement also renders more convenient the described connection of studs 45 to the loading coils. The arms 52, 53 of the conductive connecting bar are therefore of unequal length in the construction here shown, each arm carrying a 30 brush 54 arranged to make contact successively with the studs of the two sets so as to connect radially opposite studs in pair successively. It is to be understood that connector bar 52, 53 is electrically connected only to that pair of studs which it connects in any given position and is otherwise electrically isolated. In the arrangement described, the circuit relation between the secondary of the oscillation transformer and 40 the loading inductance is evidently such that for any operative position of the connector bar 52, 53 a certain proportion of the secondary of the oscillation transformer is connected in series with a certain proportion of the loading inductance; and that, in general, varying the effective value of the secondary inductance by moving said connector bar or switch occasions variations in the loading inductance. It sometimes happens, however, 50 that in adjusting the tapping-off points on the secondary of the oscillation transformer for optimum performance of the transmitter under given local conditions, two of the movable clips may be moved to substantially the same point on the secondary coil; in which case the corresponding adjacent studs 44 on the rear transmitter plate represent substantially the same inductance value of the coil. Hence shifting the connector bar or switch 52, 53 from one of such adjacent studs 44 to the next does not vary the secondary coil inductance materially, while 60 it does vary the loading inductance. One end of the secondary pancake coil, in this 65 instance the outer end, may be connected in

the antenna circuit as by lead 55 (Fig. 2); while one terminal of the series of loading coils may also be connected as by lead 56 to said antenna circuit. The tapping points, in this example nine in number, of the primary 20, the secondary 21, and the loading coils 26, may be so adjusted by means of the movable contact clips, that when the connector bar 39 and the connector bar 52, 53 are in corresponding positions, the wave length 75 or, in other words, the oscillation periods of the closed and the antenna circuits, are the same.

Means are provided whereby the wave lengths of the primary and secondary circuits, that is the closed and antenna circuits, may be simultaneously changed, and to this end the rotatable connector bars or switches carried by the front and rear plates of the transmitter are mechanically connected so 80 that they may be moved simultaneously. The means here shown for accomplishing this comprise an operating shaft 57 of wood or other non-conductive material which extends through the tubular hubs 22 and 23, 90 and to which the connector bar on the rear plate of the transnmitter is secured as by pin 58. For a purpose to be explained later, the actuating connection of shaft 57 to the front connector bar 39 is effected by means 95 of feather key 59 or some equivalent means. A controlling handle 60 is suitably secured to bar 39 for the purpose of swinging the same over the studs on the front plate. As here shown, the said handle is secured in a 100 socket member 61 rigid with hub 62 of the bar 39. When the controlling handle is swung about the axis of the transmitter to move connector bar 39, shaft 57 is rotated and the connector bar 52, 53 is thereby also 105 moved simultaneously with bar 39, and change of wave length in the two circuits is therefore accomplished simultaneously. Movable stops 38' are provided to limit the movement of the controlling handle in 110 changing wave lengths. In order to prevent accidental displacement of the parts, the connector bar or switch lever 39 carries a stop 39^a which is pressed by spring 39^b against the particular stud 38 to which the 115 lever is turned.

In order to vary the coupling between the primary and secondary, means are provided for varying the coupling distance between coils 20 and 21. As here shown, this is accomplished by moving the secondary coil axially away from or toward the primary coil, this movement being permitted by the feather-key connection above described between connector bar 39 and operating shaft 120 125 57. It is desirable also to provide an arrangement in which changes in coupling may be effected from the same point of control on the transmitter as the changes in wave length. These requirements may be met me- 130

chanically in various ways, but the arrangement here shown has proved especially advantageous in practice. The operating shaft 57 is provided with a rack 63 with which meshes pinion 64 suitably mounted on rod 65, this rod constituting substantially a part of handle 60 and being rotatable therewith about its longitudinal axis in socket member 61. By turning said handle about its longitudinal axis, it is evident that pinion 64 will operate upon rack 63 to move shaft 57 forwardly or rearwardly as may be necessary for varying the coupling. Owing to the mechanical connection between the secondary and the loading coils, the latter will of course be moved simultaneously to exactly the same extent as the transmitter secondary; and hence the self-inductance of the secondary circuit, considered by itself, remains constant since there is no change in the mutual inductance between the secondary and the loading coils. It is also to be noted that the movement of the described elements as a unit prevents any twisting, short-circuiting, or variation of the inductance of the leads connecting the same.

It will be seen that the described operation of the controlling handle in varying the coupling may be carried out either alone or in conjunction with the operation of said handle in changing wave lengths; and that the operator may effect either or both movements of said handle with one hand, while his other hand is left entirely free. Apparatus of this character I believe to be broadly new in the practical wireless art.

When a certain optimum coupling distance has been found, it is desirable to be able to lock the apparatus in this position so that accidental movement of the moving parts by reason of outside disturbing influences may be prevented. This may be accomplished, for example, by mounting a locking pin 66 in socket member 61 in position to enter the spaces between the teeth of the pinion 64 when the handle 60, which is longitudinally slideable in the socket, is moved into the position shown in Fig. 5, where the pinion is locked. It is also convenient to provide readily adjustable means for holding the controlling handle either in or out of locking position. Such means may comprise a detent member 67 mounted in the socket 61 and yieldingly pressed by spring 67^a against the surface of the controlling handle or rod in such manner as to enter either of the circumferential grooves or recesses 67^b or 67^c in the handle according as the controlling handle is in or out of locking position. The handle is readily shifted from one position to the other when desired, against the yielding restraint of the detent; but accidental shifting is effectually prevented.

Under the usual operating conditions, it

is ordinarily desirable to maintain a constant coupling distance at the different wave lengths so that only one operation is needed for a change of wave length. If, for example, with the set in tune at a particular wave length, the coupling distance necessary for best operation is found to be shorter than that desired to be maintained as the constant coupling distance, the number of turns in the secondary of the oscillation transformer should be increased, and the number of turns in the loading coils decreased, sufficiently to maintain resonance, these changes being made to the extent necessary to increase the coupling distance to that desired. Located at a convenient point below the front transmitter plate as at 68, is the double throw series-parallel condenser switch which may be used to decrease the value of the capacity under ordinary conditions in the closed or primary circuit so as to make it possible to operate at lower wave lengths. When operating from the right of the front plate of the transmitter, it is most convenient to have switch 68 located at the left and to have the controlling handle or lever of the quick-change switch mechanism extending to the right, as shown in Fig. 3. As few radio operating rooms are alike as regards size, arrangement of ground, antenna connections, etc., transmitter apparatus should be designed for what might be termed universal adaptability so as to permit of great flexibility of installation. The present apparatus is of this character and with a few simple changes can be readily adapted for operation from either side of the transmitter. For this purpose the transmitter base is provided with openings 69 below the right-hand corner of the front transmitter plate, whereby the switch 68 and the leads to the condenser may be readily transferred to the other side of the apparatus. In changing the quick-change switch from the position shown in Fig. 3 to the position for operation at the left of the transmitter, the operator proceeds as follows: The pin 58 holding the rear lever or bar 52, 53 to the operating shaft is removed, and the stops 38' are turned through an angle of 90° to permit rotation of the front lever or bar 39 through an angle of 180°. Holding the rear lever 52, 53 stationary, the controlling handle or lever 60 is swung through an arc of 180°, the operating shaft 57 being thereby turned the same distance. Rear lever 52, 53 is now again secured to the shaft by replacing pin 58, and the stops 38' are again turned back to their initial positions to limit the motion of the bar 39. The flat or pancake coils mentioned above are of spiral construction and have particular advantages for the purposes sought. Said coils consist of a flat ribbon conductor 70' spirally wound and carried by a frame comprising insulator 130

tubes 70 which are mounted radially on an insulator hub such as 22, 24 in Fig. 6. These tubes have parallel transverse grooves or slots 71 therein into which the edge of the 5 conductor ribbon is inserted as the coil is wound. To prevent the conductor from being pulled out of these grooves, the conductor is tongued at suitable intervals before winding, as indicated at 72. When the ribbon is inserted into the groove the tongue is pressed flush with the surface of the conductor; but after the tip of the tongue has passed the inner surface of the tube, the pressure is released and the tongue springs 10 outwardly, thus locking the conductor in place on the insulator tube. The ends of the tube may be closed by plugs 73 of wood or the like.

Another method of mounting the flat conductor ribbon is illustrated in Fig. 10. According to this construction, round headed screws 74 are fastened to the insulator tubes; and into the slots of these screws the edge of the band or ribbon conductor is soldered. 20 The screws are located in such manner as to give a spiral coil, ordinarily of uniform pitch.

Although of special utility in the apparatus here shown, the pancake coils above 30 described are of general application wherever coils of this form can be usefully employed for inductance, or for other purposes such as resistance.

The relation of the circuits involved in 35 the transmitter apparatus as above described is shown diagrammatically in Fig. 11 where 75 and 76 represent the primary and secondary, respectively, of a resonance transformer supplying energy to the closed circuit comprising spark gap 77, condenser 78, 40 series-parallel condenser switch 79, variometer 80, and the primary 20 of the oscillation transformer. The antenna circuit includes the secondary 21 of the oscillation 45 transformer, loading coils 26, and antenna 81, the circuit being grounded as indicated at 82. The quick-change switch is diagrammatically indicated at 84, movable contact 85 corresponding to switch lever 39 on the 50 front plate of the transmitter, and movable contact 86 corresponding to switch lever 52, 53 on the rear transmitter plate. As indicated, the tapping-off points on the primary and secondary of the oscillation transformer 55 and on the loading coils are individually variable for purposes of adjustment. 81^a is the lightning switch, while switch 81^b serves to connect the antenna either to the transmitter or to a receiver at 81^c.

60 In Fig. 12 is illustrated another form which the quick-change switch mechanism may assume. This form has been successfully used in connection with a transmitter system of which the circuit relations are 65 illustrated in the diagram of Fig. 13. Re-

ferring to Fig. 13, 100 and 101 represent the primary and secondary, respectively, of a resonance transformer, the end turns 102 of the secondary being here shown as air insulated. 70 103 is a condenser, 103^a a quenched spark gap, 104 a primary helix, and 105 a movable coupling coil in series therewith. By means of lightning switch 106, the antenna 107 may be connected either to ground or to lead 107^a for connection by means of 75 switch 108 either to a receiver system indicated at 109, or to the antenna circuit of the transmitter system at 110, said antenna circuit including variable inductance 111 and the secondary 112 of the oscillation trans- 80 former, and being connected to ground through the primary helix and coupling coil. A hot wire ammeter 113 may be inserted in the ground connection.

As indicated in the drawing, the helices 85 104 and 112 are tapped off at appropriate points and connected to four groups of contact points designated (A B C D E), (a b c d e), (A' B' C' D' E'), and (a' b' c' d' e'). These taps are arranged in such manner that 90 the primary and secondary transmitter circuits remain in syntony for any position of the movable switch devices 114 and 115. Operation of switch device 114 changes the wave length in both circuits simultaneously 95 in large steps; while shifting switch device 115 gives changes in small steps intermediate the wave lengths represented by any two consecutive positions of switch device 114.

The coupling coil 105 is so mounted on a 100 movable shaft or the like indicated at 116 that its angular position relative to the primary of the oscillation transformer may be varied to change the coupling.

The mechanical devices diagrammatically 105 illustrated in Fig. 13 for controlling wave lengths and coupling are conveniently embodied in the arrangement illustrated in Fig. 12 in such manner that from one point of control on the transmitter the wave lengths 110 in both the primary and secondary circuits may be varied without disturbing syntony, and the coupling may also be changed either alone or in conjunction with the changes in wave length. In this showing, the contact 115 points corresponding to the points at which the helices are tapped off are lettered to correspond with the same points shown in Fig. 13. Contact brush 117 of the primary helix and contact brush 118 of the secondary helix 120 are one piece mechanically and are placed in opposite directions on one arm operable by means of lever 119. By swinging said lever through the arc of a circle, the contact brushes are thereby moved simultaneously 125 and the wave lengths in both circuits are changed simultaneously in relatively large steps. Handle 119 is provided with a beveled gear 120 which meshes with beveled gear 121 on a disk 122 which is operatively 130

connected with coupling coil 105 (Fig. 13) in such manner that when the disk is revolved, the coupling is varied. Handle 119 may be turned about its longitudinal axis 5 to revolve said disk through the agency of the beveled gears before described, and hence is operable not only to vary the wave lengths in quick succession over a comparatively large range, but is also operable to 10 alter the coupling. If the handle or lever is permanently connected to bevel gear 120, when said handle is swung through an arc to move contact brushes 117, 118, the engagement of bevel gears 120, 121, will compel coupling disk 122 to turn at the same time, provided said handle is held against turning movement about its own longitudinal axis. If the handle be permitted to turn about its 15 own axis during the swinging movement, however, the bevel gear 120 simply turns idly in mesh with bevel gear 121, without moving the coupling disk.

The fine adjustment of the wave lengths may be accomplished by turning the wheel 25 123 to move contact brushes 124 and 125 through the agency of beveled gears 126, 127, and insulated connecting shaft 128.

It is evident that wheel 123 may be left in any one position and lever 119 operated to give five different wave lengths; or lever 119 may be left in one position and the wheel turned to move brushes 124 and 125 over their contact points, whereby another set of five wave lengths may be obtained in quick 30 succession, these latter wave lengths, however, being intermediate two consecutive wave lengths obtainable by operation of lever 119. In this way without disturbing the tune of the set, the whole operating range 35 of wave lengths may be swept with great rapidity by the operator, while at the same time adjustment to any particular wave length may be quickly and accurately secured. The transmitter may therefore be 40 adjusted readily to any wave length desired without the necessity of several distinct operations and without recourse to charts or diagrams for purposes of calculation. The arrangement also evidently affords effective 45 means for interference when desired.

An intermittent gear 129, 130 may be also provided whereby, after each complete revolution of wheel 123, the lever 119 is automatically advanced to the next contact 50 point. In this way twenty-five different wave lengths may be obtained by turning wheel 123 continuously through five complete revolutions. A suitable wave length scale may be provided as at 131. Part of 55 the subject matter described and claimed herein is disclosed in my prior application, Ser. No. 569,324, filed June 28, 1910.

What I claim is:

1. Wireless transmitter apparatus comprising an oscillatory circuit containing the

primary of an oscillation transformer, an antenna circuit containing the secondary of said transformer, sets of contacts electrically connected, respectively, to said primary and secondary and representing different inductance values thereof, contact members connected in said circuits and movable to engage contacts in said sets, and common means operable to move a pair of said contact members simultaneously to vary the wave length while maintaining substantial syntony. 70

2. Wireless transmitter apparatus comprising an oscillatory circuit containing the primary of an oscillation transformer, an antenna circuit containing the secondary of said transformer, sets of contacts respectively connected to tapping-off points on said primary and secondary, contact members connected in said circuits and movable to engage contacts in said sets, and common means operable to move a pair of said contact members simultaneously to vary the wave length while maintaining substantial syntony. 75

3. Wireless transmitter apparatus comprising an antenna circuit, an oscillating circuit associated therewith, variable tuning means in each circuit, sets of contacts electrically connected to said tuning means and representing, respectively, different electrical values thereof, contact members respectively movable over said sets of contacts and included in said circuits, and common means operable to move said contact members simultaneously to vary the electrical period of said circuits according to a regular relation. 90

4. Wireless transmitter apparatus comprising an antenna circuit, an oscillating circuit associated therewith, variable tuning inductance in each circuit, sets of contacts electrically connected to said tuning inductances and representing, respectively, different electrical values thereof, switch members each movable over a set of said contacts for syntonizing said circuits, and common means whereby said switch members may be moved to vary the electrical period of the circuits simultaneously. 95

5. A circuit arrangement comprising operatively associated oscillatory circuits including variable tuning means, a variable coupling between said circuits, and a controlling member operable to vary either said tuning means or said coupling. 100

6. A circuit arrangement comprising operatively associated oscillatory circuits including variable tuning means, a variable coupling between said circuits, and a controlling member operable to vary either said tuning means or said coupling, or to vary both together. 110

7. Wireless apparatus comprising two oscillatory circuits, an oscillation transformer 115

- having its primary in one circuit and its secondary in the other, sets of contacts connected, respectively, to tapping-off points on the primary and secondary of said transformer, switch members movable to engage contacts in said sets and thereby to place in circuit different inductance values of said primary and secondary, and an operating handle mechanically connecting a pair of 5 said switch members and operable to move them simultaneously into engagement with the corresponding contacts to vary the wave length while maintaining substantial sympathy.
15. Wireless transmitter apparatus comprising an oscillation transformer, loading inductance in circuit with the secondary thereof, members movable to vary the self-inductance of the primary and secondary, 20 respectively, the circuit relation between said secondary and said loading inductance being such that the latter varies when the secondary is varied, and means mechanically connecting said members and operable 25 to move the same simultaneously.
9. Wireless transmitter apparatus comprising the combination, with an oscillation transformer, and means for maintaining the primary and secondary thereof a fixed distance apart, of loading inductance in circuit with said secondary, and means for varying the self-inductance of said primary, and of 30 said secondary, the circuit relation between said secondary and said loading inductance being such that variations in the former occasion variations in the latter.
10. Wireless transmitter apparatus comprising an oscillation transformer of which the secondary is so mounted as to be movable 40 with respect to the primary, and loading inductance in circuit with and in fixed relation to said secondary and movable therewith.
11. In wireless transmitter apparatus, the combination, with an oscillation transformer comprising inductively associated primary and secondary coils, and a loading coil in circuit with the secondary coil, of means mechanically connecting said secondary coil and said loading coil for simultaneous movement with respect to said primary coil without altering the position of the secondary coil relative to the loading coil.
12. In wireless transmitter apparatus, the combination, with an oscillation transformer comprising inductively associated flat primary and secondary coils in axial alinement, and a loading coil in circuit with said secondary coil and arranged with its axis substantially at right angles to the axis of said secondary coil, and means mechanically connecting said secondary coil with said loading coil for simultaneous movement with respect to said primary coil.
13. In wireless transmitter apparatus comprising an oscillation transformer of 65 which the primary and secondary are so mounted as to be relatively movable to vary the coupling, in combination with loading inductance in circuit with said secondary and in fixed position relative to said secondary, whereby the coupling may be varied without altering the self-inductance of the secondary circuit.
14. Wireless apparatus comprising the combination with an oscillation transformer, 70 and mechanism for adjusting the coupling distance between the primary and secondary coils thereof, of means for locking said mechanism for any adjusted position of said coils.
15. Wireless transmitter apparatus comprising the combination with an oscillation transformer, of loading inductance in circuit with the secondary thereof, the inductance of said secondary and the loading inductance being adjustable with respect to each other for operation at a constant optimum transformer coupling distance, and common means operable to vary simultaneously the primary inductance and the 85 combined secondary and loading inductance for different wave lengths.
16. Wireless transmitter apparatus comprising the combination with an oscillation transformer, and loading coils in circuit 90 with the transformer secondary, of common switch means operable to vary simultaneously the effective inductance of the transformer primary, the transformer secondary, and the loading coils, respectively.
17. Wireless transmitter apparatus which comprises, in combination, a pair of flat spiral coils constituting the primary and secondary of an oscillation transformer, switch levers operable to vary the effective inductance of said coils, and mechanism operable either to vary the coupling distance between the coils, or to move said switch levers to vary the effective inductance of both coils simultaneously.
18. Wireless transmitter apparatus which comprises, in combination, a pair of flat spiral coils constituting the primary and secondary of an oscillation transformer, switch levers operable to vary the effective inductance of said coils, and mechanism operable to vary the coupling distance between the coils and at the same time to move said switch levers to vary the effective inductance of both coils simultaneously.
19. Wireless transmitter apparatus comprising, in combination, an oscillation transformer having flat spiral primary and secondary coils each supported on a frame carried by a central hub, separate sets of contact points associated with said coils, each set electrically connected with selected points on the corresponding coil, a switch

lever for each set, and means extending through said hubs and operable to move said switch levers simultaneously.

20. Wireless transmitter apparatus comprising the combination with an oscillation transformer, and loading coils for the secondary circuit, of a set of contacts electrically connected to tapping points on the transformer primary, a switch device operable to move over said contacts, a second set of contacts electrically connected to points on the transformer secondary, a third set of contacts electrically connected to points on said loading coils, a switch device operable to connect in series corresponding pairs of contacts in said second and third sets, and means for operating both switch devices simultaneously.

21. Wireless transmitter apparatus comprising, in combination, a pair of flat spiral coils constituting the primary and secondary coils of an oscillation transformer and mounted on insulator frames, insulator hubs carrying said frames and arranged in substantially axial alinement, the hub for the primary coil being stationarily mounted and the hub for the secondary coil being mounted for axial movement relative to the primary, loading coils associated with the secondary coil and mounted for movement therewith, switch means movable to bring variable proportions of the secondary coil and of the loading coils into circuit, switch means movable to bring variable proportions of the primary coil into circuit, a shaft connecting said switch means for simultaneous operation thereof, said shaft being slideable through the stationary hub and secured against axial movement relatively to the movable hub but revolute relatively thereto, and a controlling handle operable either to rotate said shaft for simultaneous operation of said switch means, or to move said shaft longitudinally to vary the coupling distance between said primary and secondary coils.

22. Wireless apparatus comprising a pair of coils arranged to constitute an oscillation transformer, in combination with separate sets of contacts, one set for each coil, leads connecting each set of contacts to tapping points on the corresponding coil, and interconnected switch means cooperating with said contacts.

23. Wireless apparatus comprising a pair of flat spiral coils mounted in parallel spaced relation and constituting an oscillation transformer, in combination with plates, one for each coil, located conveniently adjacent said coils, a set of contacts carried by each plate, leads connecting each set of contacts with adjustable tapping points on the corresponding coil, and interconnected switch means cooperating with the contacts carried by each plate.

24. Wireless apparatus comprising a pair of flat spiral transformer coils mounted in parallel spaced relation and capable of relative movement in an axial direction, a pair of plates disposed on the non-adjacent sides of said coils, each plate being fixed in position relative to its corresponding coil, a set of contacts on each plate, leads connecting each set of contacts with tapping points on the corresponding coil, and interconnected switches cooperating with the sets of contacts.

25. Wireless apparatus comprising a pair of relatively movable coils associated to constitute an oscillation transformer, two sets of contacts, each set connected to tapping points on one of said coils and fixed in position relative to such coil, and interconnected switch means cooperating with said contacts.

26. Wireless apparatus comprising a primary transformer coil, switch means associated therewith and cooperating with tapping points on said coil, a secondary transformer coil, and switch means associated therewith and cooperating with tapping points thereon, each coil being fixed in position relative to its associated switch means, but movable together with its associated switch means relatively to the other coil, means to vary the transformer coupling, and common means operable to actuate both said switch means simultaneously and to actuate the means for varying the coupling.

27. Wireless apparatus comprising a primary transformer coil, switch means associated therewith and cooperating with tapping points on said coil, a secondary transformer coil, switch means associated therewith and cooperating with tapping points thereon, each coil being fixed in position relative to its associated switch means, but movable together with its associated switch means relatively to the other coil, and means to vary the transformer coupling, and a common controlling member located on one side of one of the coils for operating both said switch means.

28. Wireless apparatus comprising a primary transformer coil, switch means associated therewith and cooperating with tapping points on said coil, a secondary transformer coil, switch means associated therewith and cooperating with tapping points thereon, each coil being fixed in position relative to its associated switch means but movable together with its associated switch means relatively to the other coil, and means to vary the transformer coupling, and a common controlling member located on one side of one of the coils for operating both said switch means and also for varying the coupling.

29. Wireless apparatus comprising the combination, with flat spiral coils in parallel spaced relation and relatively movable in

an axial direction, and switch means for each coil operable to vary the effective inductance thereof, of a rotatable element mechanically connecting said switch means and 5 movable longitudinally, a rack carried by said element, a pinion capable of meshing therewith, and a controlling handle operable to rotate said element and thereby to move said switch means, and also operable to turn 10 said pinion and thereby to move said element longitudinally and vary the coupling distance between the coils.

30. Wireless apparatus comprising the combination, with an oscillation circuit, and 15 an antenna circuit associated therewith, of common means operable to vary the wave length in both circuits simultaneously in relatively large steps, and common means for varying the wave lengths in both circuits 20 simultaneously in smaller steps intermediate the larger steps.

31. In a system of wireless signaling, the combination, with an antenna circuit, of two inductance devices included in the an-

tenna circuit, a series of contact devices for 25 each inductance device, the contact devices of each series being spaced in regular order, a conductor connected to each contact device, a variable connector connected to each conductor and arranged to be adjustable 30 over a corresponding section of its respective inductance device, and movable means common to both series of contacts for making a conductive connection from any desired contact device of one series to an operatively 35 related contact device of the other series.

32. Wireless apparatus comprising an antenna system containing capacity and inductance, an oscillatory system containing capacity and inductance, a coupling for said 40 systems and common means for simultaneously connecting said capacity, inductance and coupling to vary the oscillation period while maintaining each system substantially in syntony.

In testimony whereof I hereunto affix my signature.

FRITZ LOWENSTEIN.
